UNITED STATES PATENT OFFICE.

NIELS M. HANSEN, OF TOLEDO, OHIO, ASSIGNOR TO PAUL F. REICHERT, OF TOLEDO, OHIO.

FILM-HOLDER.

1,266,254.

Specification of Letters Patent. Patented May 14, 1918.

Application filed August 25, 1915. Serial No. 47,255.

To all whom it may concern:

Be it known that I, NIELS M. HANSEN, a citizen of the United States of America, residing at Toledo, Lucas county, Ohio, have 5 invented new and useful Film-Holders, of which the following is a specification.

This invention relates to handling of cylindrical windings of material.

This invention has utility when incorporated in devices for holding spools or reels 10 of ribbon, as motion picture films.

Referring to the drawings:

Figure 1 is a fragmentary front view of an embodiment of the invention in a motion 15 picture machine as holding the film in a center delivery reel in the supply magazine;

Fig. 2 is a view of the holder, apart from the reel, portions being broken away;

Fig. 3 is a view of the holder adjusted to 20 interlock with the reel, portions being broken away;

Fig. 4 is a view, on a smaller scale, of the opposite side or back of the holder at the adjustment shown in Fig. 3;

Fig. 5 is an enlarged detail view of the 25 lock for maintaining the device in adjusted position;

Fig. 6 is a section on the line VI—VI, Fig. 2, showing the reel in position on the holder;

Fig. 7 is a fragmentary perspective view 30 of the flexible embracing members and their mounting. Fig. 8 is a view from the right of Fig. 6 with the disk 7 removed together with the embracing section and operating 35 means therefor, the hub 5 being shown in expanded position;

Fig. 9 is a view similar to Fig. 8, on an enlarged scale but with the hub in collapsed position;

Fig. 10 is a fragmentary view of the opposite side of disk 6 from the showing in Fig. 9; and

Fig. 11 is a fragmentary perspective view 40 of the guide means in the delivery of strip material from the reel.

The driving projecting device 1 for motion picture film or ribbon 2, may have mounted thereon the magazine 3 concentrically disposed within which is the spindle or axle 4.

The reel comprising the hub 5 and parallel 50 side members or disks 6, 7, is mounted on the spindle 4 (Fig. 6).

The disk 7 has sets of diverging guide ways 8 extending centerward, while nearer the center stops or openings 9 are provided. 55

Mounted on the axle 4, and fixed therewith is the base member or disk 10 having on its side toward the disk 7, the stop or projection 11 for entering a recess 9 and thus fixing the reel in determined angular relation as to the base member 10 of the holder device. 60

The base 10 has the centerward extending, curved, converging guide ways 12, while between each pair of these ways 12, the base 10 65 has a radially extending guide way 13. The ways 12 are brought by the stops 9, 11, into registry with the ways 8 of the disk 7.

Back of the base 10 is the actuator or co-axial disk member 14 rotatably mounted on 70 the axle 4 parallel to the disk 10. This disk 14 has a curved or spiral guide way 15 for each set of guide ways on the base disk 10. Radially extending from the member 14 is the arm 16 having a threaded opening 17 75 therein with a free spring extension 18 folding back thereover to be forced by the thumb screw 19 to grip the disk 10 and thereby lock the relatively shiftable disks 10, 14, against rotation as to each other. The screw 19 is 80 guided by the bracket 20 mounted on the arm 16.

Operative connections between the disks 10, 14, are effected by the pins 21 in the ways 15 of the actuator disk 14. Each pin 21 85 has two links 22 extending therefrom to act as a toggle in spreading the levers 23 connected by the pin 24. To direct the action of this floating linkage 22, 23, the pins 21, 24, are guided by the guide ways 13 of the base 90 member 10. Accordingly as the disk or actuator 14 is rotated to cause the pins 21 to travel in the ways 15 inwardly, the toggle from its closed-in position of Fig. 2, is opened out as shown in Fig. 3, simultaneously spreading apart the free ends of the levers 23 carrying the pins 25 operating in the ways 12 of the base 10, as well as the 95

ways 8 of the reel disk 7, when adjacent thereto, serving thereby to interlock the reel with the holder or gripping device.

Fast to each pin 25 and extending inside the pin 25 of the same pair of levers 23 is a flexible embracing means or member 26. In this grouping, these adjustable arc members 26 connect fourth pins 25 with each other. In the adjustment of the gripping device, these members 26, by the one-motion or single movement of the arm 16, vary the cylindrical adjustment in approximating a true circle for positively gripping and concentrically sustaining a film in a film holding reel. The reel section comprising the hub 5 and the disks 6, 7, is a unit independent of the straps 26 and their operating means through the relatively rotatable disks 10, 14, and the coöperative anchoring slots 8 against relative rotation in the disk 7. This reel section comprising the disks 6 and 7 and the hub 5 may be the structure upon which the film, say in a moving picture apparatus, is wound for exhibiting and as so used for receiving the film there is not present the strap or adjustable arc members 26 with their operating means, the peripheral way being clear. These arc members and their operating means may be applied subsequently to the charging of the reel section comprising the hub 5, disks 6, 7. The disk 6 has mounted thereon the hub comprising the movable sections 27, 28 and 29. The section 29 is mounted on the fixed pivot 30 and has actuating pin 31 movable in the slot 32 of the disk 6.

The section 27 has the pin 33 slidable in the slot 34 of the disk 6. This section is engaged by the operating pin 35 slidable in the slot 36. The section 28 has the pin 37 slidable in the slot 38 in the disk 6 as its guide pin and is actuated by the pin 39 movable in the slot 40 of the disk 6. These actuating pins 39 and 35 are fast with the operating arm 41 rockable on the axle sleeve 42, while the actuating pin 31 operates in the slot 43 in the actuating arm 41. The free end of this arm 41 has reciprocable thereon on the T-shaped member 44 provided with the guide slots 45, 46, coacting with the pins 47, 48, carried by the arm 41. This slidable member 44 is normally held retracted inward by the spring 49 with its cross ledges 50, 51, coacting with the cross bar 52 of the trigger 53 pivoted upon the pin 47, whereby rocking of this trigger 53 against one of the ledges 50 or 51 will lift this member 44 against the action of the spring 49 to free the holding notch 54 from the pin 55 in one direction and the opposite notch 56 from the pin 57 in operating the arm 41 for swinging in the other direction.

With this actuator 41 locked with the pin 55, the hub is in expanded position and the

spring 58 (Figs. 8 and 9) rocks the dog 59 into engagement with one of the quadrant disposed recesses 60 on the hub 61 fast with the disk 7 so that the slots 8 are in proper angular position for a registry with the embracing mechanism. As this actuator 41 is locked to have the recess 56 engage the pin 57, the hub is collapsed by the inward movement of the three sections and the resulting simultaneous withdrawal of the dog 59 is positively actuated by the pin 35. This releases the disk 7 for freedom of rotation with the material and the outward embracing means, while leaving the disk 6 locked against rotation by ledge 61' engaging in the housing for the withdrawal of the strip material from the two reel sections.

When the actuator 41 was in position as held by the pin 57, the hook 62 rigid therewith engaged the pin 63 on the arm 64 swingable in the arc slot 65 of the disk 6. Upon the throwing of the actuator 41 into position as held by the pin 55, this hook 61 was rocked to release the pin 62, thereby allowing the spring 66 coacting about the arc 67 to pull the arm 64 for outward travel in the slot 65 carrying with it the roller 68 coacting with the inner portion of the peripherally held material. Before actuation of this member 41, the arc members 26, with their actuators, have been brought into assembled relation for close gripping engagement peripherally of the roll of material 2, and the outward throwing of this roller 68 holds this strip material from full collapse and serves as a guide roll for the strip 2 in passing thereunder, thence over the angular rigid guide 69 for delivery by the roller 70. The threading of this free inner end of the strip material is permitted by swinging outward the gate 71 on its hinge 72, said outward swing carrying with it the rigid guide 69 as well as the roller 70. When brought back into closed position, this door 71 is held by the latch 72.

In operation, the reel which is just loaded by receiving the film exhibited is removed from its magazine, usually the one below the projecting apparatus, its hub is slipped over the axle 4 of the embracing holder or gripping device, the stops 9, 11, being brought into registry and engaging. The reel or the base 10 may be held while the arm 16 is rotated clockwise, thus causing the pins 21 to spread the links 22 and levers 23, and as the pins 21, 24, are guided by the ways 13, 120 the actuating ways 15 cause the pins 25 to move in the ways 12 and thence into the registering ways 8, increasing the overlap of the ends of the members 26, thereby reducing the effective diameter of the gripping means until the film is firmly engaged. The set screw 19 may then be rotated to effect friction locking between the actuator 14 and

the base 10, and the loaded reel is ready for shipment or charging into the supply magazine 3 for central delivery therefrom of film 2. This operation is simply, effectively and most rapidly performed without any necessity for rewinding of stock or film, and the film load is sustained as a hard compact mass away from the central delivery way, thus insuring freedom for outward travel at all times with no liability of injuring the fragile combustible ribbon.

What is claimed and it is desired to secure by Letters Patent is:

1. A reel for strip material, and a one-motion operable peripheral embracing means embodying interconnected simultaneously actuatable elements for externally gripping strip material on the reel.
2. An adjustable cylindrical centerward gripping device embodying a base, and operating means embodying interconnected simultaneously actuatable elements movable relatively to the base for effecting gripping peripheral adjustment of the device.
3. An adjustable cylindrical gripping device embodying peripherally disposed flexible arc gripping members, and a base providing guiding means therefor.
4. An adjustable cylindrical gripping device embodying peripherally disposed flexible arc embracing means, a base providing guiding means for the embracing means, and actuator means for moving the embracing means relatively to the base.
5. An adjustable gripping device embodying interconnected simultaneously operable embracing means, an embracing means guiding base, and a positive actuator shiftable relatively to the base for varying the adjustment of the embracing means.
6. An adjustable gripping device embodying embracing means, and coaxial relatively angularly shiftable guide members having interengaging means coacting for varying the adjustment of the embracing means.
7. An adjustable centripetal gripping device embodying a peripheral series of embracing means, a base having guide ways extending away from the center thereof, and a relatively angularly shiftable actuator for simultaneously moving the series of means as directed by the ways.
8. An adjustable gripping device embodying embracing means, a base having diverging guide ways, and a relatively shiftable actuator having guide means and connections for effecting simultaneous adjustment of the embracing means in a plurality of the base guide ways.
9. Peripherally extending flexible arc embracing means, relatively shiftable guiding members, and intermediate linkage operable by the shifting of the members to vary the adjustment of the means.

10. A reel for strip material and in addition to the reel a material centripetal embracing device provided with means for mounting concentrically of the reel independently of the reel.

11. A reel for strip material and in addition to the reel a material embracing device embodying flexible embracing means and a base for supporting means coaxially with the reel.

12. A reel for strip material and in addition to the reel a gripping device embodying adjustable embracing means for material on the reel, and a base for the means adjustable to determined angular relation as to the reel.

13. A reel having guide means and in addition to the reel a gripping device embodying adjustable embracing means for reel held material, and a support for said embracing means, said device in the adjustment of the embracing means interlocking with the guide means of the reel.

14. A reel having guide means and in addition to the reel a stop, and a reel held material gripping device embodying adjustable embracing means and a stop registerable angularly with the stop of the reel, whereby in the adjustment of the embracing means of the device the guide means of the reel effect interlocking of the reel with the device.

15. A reel in addition thereto, an adjustable embracing device for reel held material, and means coacting upon adjustment of the device as to the reel to lock the reel to the device.

16. A center delivery film reel, and a film centripetal embracing device peripherally extending for exteriorly coacting in simultaneous positive adjustment in centering the film in the reel.

17. A one-motion external gripping device embodying simultaneously operable interconnected elements for centering reel-held films.

18. A one-motion gripping device embodying simultaneously operable interconnected elements for centering reel-held films, and means for rigidly locking the device in position.

19. A plural strip flexible band gripping device for centering reel-held films, and reel centering and interlocking means therefor.

20. A reel comprising a first centerward controlling section, and a second peripheral controlling section circumferentially adjustable as a unit for embracing material in the reel on the centerward controlling section.

21. A reel comprising a first centerward controlling section, and a second peripheral controlling section, one of said sections including operating means for effecting simul-

- taneous adjustment of said section throughout its extent.
22. A reel comprising a first centerward controlling section, a second peripheral controlling section, and positive adjusting means for the sections, one of said adjusting means embodying elements for simultaneously shifting such section throughout its extent. 5
23. A reel comprising a first centerward controlling section, and a second peripheral controlling section, one of said sections embodying adjusting means simultaneously co-acting throughout the circumferential extent of such section. 10
24. A reel comprising a first centerward controlling section, and a second peripheral controlling section, one of said sections embodying adjusting means simultaneously co-acting throughout the circumferential extent of such section to be withdrawn from engaging a charge of material on the reel. 15
25. A holding device for a coil of strip material embodying peripheral engaging means for the material, a pair of adjacent supporting disks for the means, said disks provided with intersecting slots, and control elements for the means mounted in the slots whereby relative angular shifting of the disks may effect adjustment of the means. 20
26. A reel for a coil of strip material, said reel including a disk provided with slots, and a holding device for the strip material coil embodying peripheral engaging means for the coil, control elements for the means, and a pair of independently movable slotted engaging disks, said control elements coacting with the slots of the disks to effect adjustment of the means and lock the device in position as to the reel. 25

In witness whereof I affix my signature.

NIELS M. HANSEN.

Copies of this patent may be obtained for five cents each, by addressing the "Commissioner of Patents, Washington, D. C."

It is hereby certified that in Letters Patent No. 1,266,254, granted May 14, 1918, upon the application of Niels M. Hansen, of Toledo, Ohio, for an improvement in "Film-Holders," errors appear in the printed specification requiring correction as follows: Page 3, line 27, claim 3, for the word "are" read *are*; same page, line 50, claim 7, strike out the word "angularly"; same page, line 55, claim 8, after the word "relatively" insert the word *angularly*; same page, lines 88-89, claim 14, strike out the words "in addition to the reel"; same page and claim, line 89, after the word "and" insert the words *in addition to the reel*; page 4, line 15, claim 23, after the word "section" insert the words *to engage a charge*; and that the said Letters Patent should be read with these corrections therein that the same may conform to the record of the case in the Patent Office.

Signed and sealed this 11th day of June, A. D., 1918.

[SEAL.]

F. W. H. CLAY,
Acting Commissioner of Patents.

Cl. 88—18 7.
